CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK

LOOSE-LEAF BINDER

Application filed December 16, 1930. Serial No. 502,636.

This invention relates to so-called ring binders for loose-leaf books. Such binders comprise separable rings, the segments of which (hereinafter called prongs) are carried upon movable supports, usually in the form of flat plates, which have a rocking engagement at their inner or adjacent edges and are pressed toward each other, their relation being such that their movement between the closed and open positions of the rings carries them past an intermediate or neutral position or plane so that the spring stress acts through the plates to hold the prongs apart when open and to hold them pressed together when closed. Such plates are commonly called toggle plates, because they have an effective toggle action as they move in either direction past their neutral or mid position. The spring stress may be variously imparted but is most commonly applied by means of a resilient sheet-metal back plate, the outer edges of which are turned inwardly to form hooks or concave longitudinal flanges which embrace the outer edges of the prong plates and form, in effect, rocking pivots at their engagement therewith. In some instances, however, the resilience is provided within the material of the prong plates themselves, which is to be regarded as an equivalent of the resilient back plate. In some cases, also, the structure is covered over with a top plate or cover plate which may itself be the resilient member or may, by its spring stress, supplement that of the back plate.

Such toggle prong plates as heretofore made have had a rocking or knife-edge engagement with one another at their meeting or adjacent edges. The present invention substitutes for this a varying rocking engagement by means of cam surfaces formed upon or projecting from the meeting or adjacent edges of the plates. These cams are so shaped that as the prongs open by the rising movement of the plates the rocking engagement of the cam faces presses the plates apart while causing their points of contact to descend relatively to the plates. The result is that their effective contact is brought much nearer to the medial line or neutral plane when the prongs

are opened than when they are closed. This has the further effect of giving a very much lighter effective spring stress to hold the prongs open than that which acts when they are closed together to hold them closed.

It is common with ring binders of this type to provide some sort of opener (sometimes called a booster) for forcing the plates up at their adjoining edges to open the rings. Such opener is constructed to provide an adequate leverage for overcoming the stiffness of the spring member by which the prongs are held closed together. It is desirable that the springs stress be such as to hold the hooks together with considerable firmness in order to avoid any possibility of their separating and spilling out the leaves or sheets, as well as to make provision for the gradual loss of spring stress which occurs in the course of time. With the ordinary binders the provision of such stiffness results in making it very difficult to press the prongs together to close the rings. The present invention has the effect of greatly diminishing the effective spring stress when the prongs are opened while applying the maximum spring stress to hold the prongs closed. The preferable embodiment of the invention is that shown in the accompanying drawings, wherein—

Figure 1 is a transverse section of the loose ring mechanism in open position, taken on line 1—1 in Fig. 3, the usual cover and the means for attaching the loose mechanism to the cover being omitted from the drawings.

Fig. 2 is a longitudinal mid-section of one end portion of the binding mechanism.

Fig. 3 is a plan of the binding mechanism showing the prongs separated as in Fig. 1, a portion of the cover plate being broken away to better show the internal construction.

Fig. 4 is a transverse section similar to Fig. 1 but on line 4—4 in Fig. 3, and with the prongs closed.

Figs. 5 and 6 are transverse sections much enlarged, showing, respectively, the closed and open positions of the prongs, these views being in the plane of the line 5—6 in Fig. 3.

Fig. 7 is a fragmentary plan and edge view showing the cam on one of the prong plates.

Fig. 8 is a similar plan and edge view of a modified shape of cam.

According to the drawings, A, A are the usual prongs or half-rings, sometimes called hooks, and B, B are the prong plates or toggle plates which carry them. These, as stated, have a rocking engagement at their approaching edges and turn upon substantially fixed axes at their outer edges where, in the 10 preferred construction, they are embraced between the inturned hook flanges or channels c, c of the spring back plate C. A cover plate D is applied in such manner as to cover over and conceal the mechanism and is commonly formed with outer hooked flanges d, d to embrace the flanges c, c. As stated, the resilient effect may reside in the back plate C or it may be in the cover plate D, or it may be partly in each. Commonly, it is the back 20 plate C which is mainly relied upon as the spring plate. In some instances in the art this back plate is so thick and stiff as to be substantially rigid, and the prong plates B, B are slotted or otherwise conformed so that 25 the resilient effect occurs within the material of these plates. These several constructions are regarded in the art as equivalents.

In the particular construction shown the prongs A, A are swaged or riveted into holes 30 formed in the prong plates. The inner or rocking edges of the plates are kept in alignment by being formed with lips b, b overlying one another, this being a construction well understood in this art. The bearing engagement 35 of the prong plates is accomplished at suitable intervals by means of cam portions E, E which project slightly beyond the edges of the plates so as to hold the latter apart slightly (as shown in Fig. 3) except where the cam portions E, E occur. These cam 40 portions E, E are preferably bent down somewhat from the main level of the plate, as shown in Fig. 2 and in Fig. 7. They are formed in pairs so that those on the right and 45 left-hand plates meet and engage each other with a rocking or rolling contact. This contact, as the plates rock, may travel from one end of the mating cams to the other, or its travel may be in the direction of the thickness 50 of the plates, this thickness being increased where the cam portions are struck down. This will be best understood from an examination of Figs. 5 and 6, which show the preferable rocking engagement of the cam surfaces. In these figures the line x, x represents 55 a plane intersecting the essential points of engagement of the outer edges of the plates with the hook flanges c, c on the back plate (or any equivalent points of engagement with 60 whatever resilient means is employed). In Fig. 5, where the prongs are closed together and the plates are down, the cams engage at the points w, w, which points are somewhat 65 remotely below the middle of the line x, x, whereas in Fig. 6, where the prongs are

separated to open the rings, the rocking engagement of the cams has brought their points of contact to the points y, y, which are much closer above the line x, x than the points w, w are beneath that line. As the 70 toggle action with respect to spring stress applied to the ends of the prongs is much more effective when the contact points (w, w) are remote from the neutral line x, x than when they are, (as at y, y) close to that line, 75 it follows that the springs stress is much more effective when the prongs are closed together than when they are opened apart.

In action, as the prongs are separated by the rising of the middle portion of the plates, 80 the effective cam contact rolls downward, while at the same time the contact surfaces pass through the plane x, x between the outer pivotal edges of the plates so that when the plates reach their neutral position their outer edges are materially separated, thereby forcing apart the flanges c, c of the spring plate; and as the plates pass this plane and move farther upward the rolling contact of the 85 cams partially preserves this separation and 90 maintains nearly the entire increased stress thus imparted to the resilient member. In this movement, of course, the effective contact points cross the medial line x, x so that the 95 spring stress is reversed in its effective direction so that in the position shown in Fig. 6, it is made effective to hold the prongs separated. By reason of the fact that the cams are struck downward from the plates it is quite practicable to carry the effective contact points y, y entirely below the lower edges 100 of the plates elsewhere, as is apparent, this being a result not heretofore attained.

Thus this invention in its practical application in effect redistributes the spring stress, 105 increasing its effect in the closed position of the prongs and diminishing its effect in their opened position; the result is that the prongs form more perfect closed rings when the book is closed, and when the prongs are separated 110 to open the rings it is much easier to close them together again than heretofore.

Since the invention makes it much more difficult than heretofore to separate the prongs, it is important to provide a suitable 115 opener affording ample leverage for the purpose. Such opener is constituted by a lever F, as shown in Figs. 2 and 3, the long arm of which overhangs the end of the top plate D and the short arm f of which comes under the adjacent edges of the prong plates by which to pry them up and open the prongs. Such opener may be variously constructed but is preferably of the construction shown and described in detail in my companion application filed November 26, 1930, Serial No. 498,268.

The shape of the cams may be greatly varied without departing from the invention. Fig. 8 is an example wherein the cam, in- 130

instead of being pressed downwardly at an incline, as in Fig. 7, is embossed downwardly, its rolling surface g being suitably rounded. This rounding may be on the same contour shown in the cross-section Figs. 5 and 6.

5 The cam surfaces may be considerably varied, the important thing being that the bearing contact of the plates is struck downward from the general plane of the plates so that their effective points of contact may vary in 10 their relation to the neutral line α , α during the movement of the plates, as has been described with reference to Figs. 5 and 6.

It is an important feature that there shall 15 be a suitable relation between the effective cam surfaces in the open position (Fig. 6) and the means for arresting the prong plates in that position. It is understood that the opening movement of the prongs is limited 20 only by the internal construction of the mechanism whereby some suitable stop is provided to limit the upward movement of the adjacent edges of the prong plates. This stop is conveniently applied to the top plate 25 D, which is shown as having internal projections h , h in position to be abutted by some portion of the inner edges of one or both the prong plates, preferably by the lips b , b which, as shown, project somewhat above the 30 top surfaces of the plates, and in the open position of the prongs strike against the stops h , as shown in Fig. 6. According to the present invention, the stops h are formed integrally with the plate D by swaging or cupping a portion of this plate downwardly in 35 the proper position, as shown in Figs. 1, 2 and 3. The positions chosen are those which coincide with the lips b , b .

The construction may be modified to a considerable extent without departing from the 40 invention, the scope of which is indicated by the claims.

In place of limiting the opening movement by the stops h , reciprocal stops may be applied to the two prong plates, an example 45 of which is shown in my Patent No. 1,468,845, dated September 25, 1923.

The present invention does not necessitate that the bearing portions or rocking engagement of the prong plates shall be limited to 50 projecting cam portions which force the inner edges of the plates elsewhere out of contact with one another. It is common in binders of this type to maintain an extended contact between the inner edges of the prong plates, an example being shown in my Patent No. 1,468,845, dated September 25, 1923; to apply my present invention to that construction, the cams E, E need only come into 55 mutual abutment as the plates in the opening movement swing to or above the neutral line α , α .

While it is preferable to form the cams E, E integrally with the prong plates by suitable swaging or bending, yet it is to be un-

derstood that the invention is not limited to this integral construction, as the cam faces might be on separate pieces united to the plates.

I claim as my invention:

1. Loose leaf binding mechanism of the type comprising prong plates having a rocking engagement at their adjacent edges, pressed resiliently together, and movable to both sides of a neutral line so as to apply the resilient stress to hold the prongs in either open or closed position, characterized by the provision of said plates with cam portions acting to force them apart in moving to the open position.

2. Binding mechanism according to claim 1, the cam portions being bent down from the material of the plates.

3. Binding mechanism according to claim 1, the cam portions projecting downwardly from the plates and abutting at points below the center of the plates.

4. Binding mechanism according to claim 1, the cam portions having their engaging faces contoured to roll on each other with a rocking engagement during the opening and closing movements.

5. Binding mechanism according to claim 1, the cam portions having their engaging faces contoured to abut above such neutral line in the open position and below such line in the closed position.

6. Binding mechanism according to claim 1, the cam portions having their engaging faces contoured to abut above such neutral line in the open position and below such line in the closed position, their abutment being nearer such line in the open position than in the closed position.

7. A loose leaf binder comprising prong plates and a spring back plate engaging their outer edges, the prong plates having projecting cam portions adapted, as the plates are moved to the open position, to force apart their outer edges against the stress of the spring plate.

8. A loose leaf binder comprising prong plates, a spring back plate engaging their outer edges, and a cover plate, the latter having stops to limit the opening movement of the prong plates, formed integrally as indented cups.

9. A binder according to claim 8, the prong plates having projecting lips and the stops on the cover plate arranged coincident with said lips for abutment therewith to limit the opening movement.

In witness whereof, I have hereunto signed my name.

CLARENCE D. TRUSSELL.
